INVENTOR,

John J. Murray.

UNITED STATES PATENT OFFICE.

JOHN J. MURRAY, OF PHILADELPHIA, PENNSYLVANIA.

HANDLE FOR SOLDERING-IRONS.

SPECIFICATION forming part of Letters Patent No. 393,444, dated November 27, 1888.

Application filed February 24, 1888. Serial No. 265,530. (No model.)

To all whom it may concern:

Be it known that I, JOHN J. MURRAY, a citizen of the United States, residing at 3524 Haverford street, in the city of Philadelphia, State of Pennsylvania, have invented a certain new and useful Fire-Proof Handle to be used on Soldering-Irons, Files, Rasps, Wood Chisels, &c., of which the following is a description.

The ordinary wooden handle used on soldering-irons becomes charred and burned by the heated iron, and soon splits and is rendered useless.

The object of my invention is to so protect the wood as to prevent it from being burned and split.

In the drawings, Figure 1 represents a sectional view of my improved handle, and Fig. 2 an elevation of same.

My invention has for its object to prevent the charring and burning of soldering-iron handles, which invariably occurs when the wooden handle is attached direct to the iron itself.

My invention, accordingly, consists of the combination, construction, and arrangement of parts, as hereinafter described and claimed.

In the drawings, A represents a soldering-iron, of which C is the handle, a the stem, a' the point, and B the casting, which I place between the handle C and stem a to protect the former. The casting B has a recess, b³, into which is inserted the stem a. At the bottom of casting B is a flange, b, into which fits one end of the handle C. In the bottom of the

recess or seat b⁵, between the part b' of casting B and the flange b, I place asbestos or other material which is a non conductor of heat. The part b' of casting B changes at b⁶ into the stem b², which projects beyond the handle C, in order to allow the nut b⁴ to be placed thereon. I do not confine myself to a nut, as a rivet or other contrivance may be used, as shown at b⁷, Fig. 2. At the bottom of casting B, I place a set-screw or other fastening device, x, to hold the stem a of iron in position.

What I claim is—

1. In combination with the soldering-iron A, the handle C, casting B, with recess b⁵, fastening device b¹, recess b⁶, and set-screw x, substantially as set forth.

2. A tool-handle comprising a tube and ferrule in one piece, a hollow handle on the tube and in the ferrule, means at the outer end of the tube and bearing on the end of the handle for securing these parts together, and a device for holding the tool-shank within the tube and ferrule, as set forth.

3. A tool-handle comprising a tube and ferrule in one piece, a hollow handle on the tube and in the ferrule, means at the outer end of the tube and bearing upon the end of the handle for securing these parts together, and a set-screw passing through the cylindrical base of the tube and ferrule, as set forth.

JOHN J. MURRAY.
